LATCH

Charles Ledin, Stamford, Conn., assignor to The
Yale & Towne Manufacturing Company, Stam-
ford, Conn., a corporation of Connecticut

Application March 9, 1946, Serial No. 653,249

15 Claims. (Cl. 292—165)

1

This invention relates to a latch, and more particularly to that type of latch that is adapted for operation by a depressible thumb piece. More particularly, my invention relates to a tubular type of latch in which the latch bolt is housed in a tube adapted for insertion in a simple bore formed in a door, and for operation by a spindle or other means inserted in a transverse simple bore.

A feature of my invention resides in the utilization of a pair of co-axially mounted rollbacks carried by the casing of the latch, with one rollback adapted for rotation by a knob operated spindle of the latch, while the other rollback is adapted for rotation by a thumb piece.

As a further feature of the invention, the spindle rotated rollback is adapted for rotation in opposed directions, and when rotated in one direction will directly retract the latch bolt, while when rotated in the opposite direction will retract the latch bolt only through the intermediary of the other rollback. It is a still further feature of this part of the invention that the said other rollback is rotated in a bolt retracting direction by operation of the thumb piece, and for the particular purpose the latch casing preferably supports for pivotal movement a lever that is contacted by the thumb piece for rotating the rollback to retract the latch bolt.

Where the thumb piece must rotate a knob and spindle incidental to its operation to retract a latch bolt, it is obvious that the thumb piece action will be quite hard. It is a further feature of the invention that the retraction of the latch bolt by the thumb piece will not effect a movement of the knob rotated spindle and knob. Therefore, the thumb piece will have a relatively easy action.

A still further feature of this part of my invention resides in the mounting of the knob rotated spindle relatively to the rollbacks so that only one rollback will be coupled to the spindle to rotate with the spindle, the other rollback being rotatable independently of the spindle to contribute the easy action of the thumb piece.

A still further feature of the invention resides in means for retaining or securing the spindle relatively to one of the rollbacks against endwise movement relatively thereto.

I have thus outlined the general nature of my invention and its relation to the prior art in order that the description thereof that follows may be better understood, and in order that my contribution to the art may be better appreciated. There are, of course, additional features of my invention that will be described hereinafter and which will form the subject of the claims ap- 55

2

pended thereto. Those skilled in the art will appreciate that the conception on which my disclosure is based may readily be utilized by those skilled in the art as the basis for the designing of other structures for carrying out the several purposes of my invention.

Referring now to the drawings, Fig. 1 is an endwise view of a door in which is mounted the latch of my invention. Fig. 2 is a section taken along lines 2—2 of Fig. 1. Fig. 3 is a view of the parts of Fig. 2 showing the latch bolt retracted by operation of the thumb piece. Figs. 4, 5, and 6 are sections taken respectively along lines 4—4, 5—5, and 6—6 of Fig. 2. Fig. 7 is an exploded view of parts of the latch.

Referring now more particularly to the drawings, the latch casing 10 of my invention is mounted within a bore 11 formed in a door D. The front of the latch casing 10 is formed with a flange 12 to which is secured a decorative plate 13, a pair of screws 14 serving to fasten the decorative plate 13 and the flanges 12 to the edge of the door and thereby to secure the casing 10 within the bore 11. Slidably mounted within the casing 10 is a latch bolt B formed with a head 15, a main body 16 and a flange 17. A latch bolt retractor 18, best shown in Fig. 7, is formed with inwardly extending shoulders 19 adapted to overlie the flange 17 so that movement of the retractor to the right from the position of Fig. 2 to the position of Fig. 3 will move the latch bolt B to the right and carry the head 15 out of locking position.

Retraction of the latch bolt B is resisted by a spring 20, best shown in Fig. 4 as lying between an abutment 21 formed as a part of the latch housing 10, and a surface 22 of the latch bolt flange 17. The movement of the retractor 18 together with the latch bolt B is resisted by a further spring 23 extending about a guide pin 24 that is supported by the abutment 21 and in a bore 25 of the retractor 18. It is obvious that movement of the retractor into the position of Fig. 3 will be in opposition to both the spring 23 and the spring 20. The mechanism so far described is conventional, and per se is not my invention herein to be claimed.

The latch casing 10 is formed as shown in Fig. 6 with a bearing surface 26 for supporting for rotation a rollback 27 best shown in Fig. 7. The casing 10 is further formed with a bearing portion 28 for supporting for rotation a rollback 29 that is also best illustrated in Fig. 7.

The rollback 29 is formed with a shoulder 30 that is adapted to cooperate with a lug 31 on the retractor 18, so that clockwise rotation of the

rollback 29 will move the retractor 18 to its position of Fig. 3 to retract the latch bolt B. The shoulder 33 is part of an extension 32 of the rollback 29, this extension being further provided with a shoulder 33 for co-action with a lug 34 on the rollback 21. Thus, when the rollback 27 is rotated clockwise, it will contact the shoulder 33 and rotate the rollback 29 clockwise, and this will, of course, effect a retraction of the retractor 18 and the latch bolt as previously described. Rollback 27, when rotated in a reverse or counterclockwise direction will retract the retractor independently of the rollback 29. Thus, the surface 34a of lug 34 will contact a second lug 35 on the retractor 18 and will move the retractor 15 to move the latch bolt to its position of Fig. 3.

For rotating the rollback 27, I utilize a spindle 36 extending from a knob 37 into a square opening 38 formed in the said rollback 27. The end of the spindle 36 is formed with a threaded bore 39 for housing a screw 40, the screw 40 holding in position a limit washer 41 that rests against the end surface of the spindle 36. It is, of course, obvious from Fig. 6 that the screw 40 and the washer 41 will prevent movement of the spindle 36 to the left outwardly of the square opening 38 of the rollback 27. It will now be readily appreciated that rotation of the spindle 36 must rotate rollback 27, and that when this rotation is counterclockwise, the surface 34a will contact the retractor lug 35 to move the retractor 18 and withdraw the latch bolt to its position of Fig. 3. It will be further obvious that when the spindle 36 is rotated clockwise, the lug 34 of the rollback 27 will contact the shoulder 33 forming part of the rollback 29 to rotate the rollback 29 clockwise. Of course, the shoulder 30 will then contact the lug 31 and move the retractor to the right from the position of Fig. 2 to the position of Fig. 3, thereby retracting the latch bolt.

It will be noted that while the spindle 36 is in driving engagement with the rollback 27, it is freely rotatable relatively to the rollback 29 because the rollback 29 is formed with a large bore 42, the surface of which is completely out of contact with the spindle 36. Therefore, rollback 29 when rotated clockwise from its position of Fig. 2 will not impart rotation to the spindle 36, and the knob 37 will not be rotated. This relationship of the parts is important because I arrange for the clockwise rotation of the rollback 29 independently of the spindle 36 by a thumb piece, thus contributing the easy action thumb piece to which I have already alluded.

Referring now especially to Figs. 1, 2, 6, and 7, I secure to the door D a handle 43, this handle being carried by a lower escutcheon plate 44 and an upper escutcheon plate 45. Suitably pivoted on the upper escutcheon plate 45 in the conventional manner understood in the art, is a thumb piece 46 having a lever portion 47. The door is cut away as at 48 to allow for free movement of that lever portion 47 between its positions of Figs. 2 and 3. Pivoted on the latch bolt casing at 49 is a lever 50 that extends through an opening 51 of the latch bolt casing 10 and is pressed by surface 32 of rollback 29 against the lever portion 47 of the thumb piece 46 as is best illustrated in Figs. 2 and 6. Upon depression of the thumb piece 46 the lever portion 47 will, of course, be raised from the position of Fig. 2 to the position of Fig. 3, and will rotate the lever 50 clockwise about its pivot 49. The surface 50a of the lever 50 will then through its contact with the undersurface of the extension 32 of the rollback 29 rotate the rollback

29 to its position illustrated in Fig. 3. Of course, the retractor 18 will be moved to the right and will withdraw the latch bolt from latching position.

It is now obvious that I provide a simple type of tubular latch having a latch bolt that is readily retractable by a knob and thumb piece, with the thumb piece retracting the latch bolt independently of the knob and without effecting any movement of the knob. Similarly, it is quite obvious that the retraction of the latch bolt by the knob will be independent of the thumb piece. I believe my invention will now be understood by those skilled in the art.

I now claim:

1. In a latch of the class described, a casing, a latch bolt slidable in said casing between a spring projected position and a retracted position, a pair of rollbacks, means mounting said rollbacks for rotation in said casing in a common axis, means whereby said rollbacks retract said latch bolt when rotated relatively to said casing, a spindle for rotating one of said rollbacks, a lever for rotating the second of said rollbacks mounted on said casing, and a thumb piece for actuating said lever.

2. In a latch of the class described, a casing, a latch bolt slidable in said casing between a spring projected position and a retracted position, a pair of rollbacks, means mounting said rollbacks for coaxial rotation in said casing, means whereby one rollback retracts said latch bolt when it is rotated in one direction, means whereby the second rollback retracts said latch bolt when rotated in a reverse direction, and means whereby the second rollback rotates the first rollback to retract the latch bolt when rotated in said one direction.

3. In a latch of the class described, a casing, a latch bolt slidable in said casing between a spring projected position and a retracted position, a pair of rollbacks, means mounting said rollbacks for coaxial rotation in said casing, means whereby one rollback retracts said latch bolt when it is rotated in one direction, means whereby the second rollback retracts said latch bolt when rotated in a reverse direction, means whereby the second rollback rotates the first rollback to retract the latch bolt when rotated in said one direction, a spindle for rotating the second rollback in both directions, and a thumb piece for rotating the first rollback in said one direction.

4. In a latch of the class described, a casing, a latch bolt slidable in said casing between a spring projected position and a retracted position, a pair of rollbacks, means mounting said rollbacks for coaxial rotation in said casing, means whereby one rollback retracts said latch bolt when it is rotated in one direction, means whereby the second rollback retracts said latch bolt when rotated in a reverse direction, means whereby the second rollback rotates the first rollback to retract the latch bolt when rotated in said one direction, a spindle for rotating the second rollback in both directions, a lever pivoted on said casing and adapted when rotated on its pivot to rotate said first rollback in said one direction, and a thumb piece for rotating said lever.

5. In a latch of the class described, a casing, a latch bolt slidable in said casing between a spring projected position and a retracted position, a pair of rollbacks, means mounting said rollbacks for coaxial rotation in said casing, means where-

by one rollback retracts said latch bolt when it is rotated in one direction, means whereby the second rollback retracts said latch bolt when rotated in a reverse direction, means whereby the second rollback rotates the first rollback to retract the latch bolt when rotated in said one direction, a spindle for rotating the second rollback in both directions, a lever pivoted on said casing and adapted when rotated on its pivot to rotate said first rollback in said one direction, said lever having a portion extending outwardly of said casing, and a thumb piece for contacting the outwardly extending portion of said lever to rotate said lever.

6. In a latch of the class described, a casing, a latch bolt slidable in said casing between a spring projected position and a retracted position, a pair of rollbacks, means mounting said rollbacks for coaxial rotation in said casing, means whereby one rollback retracts said latch bolt when it is rotated in one direction, means whereby the second rollback retracts said latch bolt when rotated in a reverse direction, means whereby the second rollback rotates the first rollback to retract the latch bolt when rotated in said one direction, a spindle traversing openings in both said rollbacks with the opening in the first rollback sufficiently large to allow free rotation of said spindle relatively thereto while the second rollback opening couples the second rollback to the spindle for rotation therewith in both directions.

7. In a latch of the class described, a casing, a latch bolt slidable in said casing between a spring projected position and a retracted position, a pair of rollbacks, means mounting said rollbacks for coaxial rotation in said casing, means whereby one rollback retracts said latch bolt when it is rotated in one direction, means whereby the second rollback retracts said latch bolt when rotated in a reverse direction, means whereby the second rollback rotates the first rollback to retract the latch bolt when rotated in said one direction, a spindle traversing openings in both said rollbacks with the opening in the first rollback sufficiently large to allow free rotation of said spindle relatively thereto while the second rollback opening couples the second rollback to the spindle for rotation therewith in both directions, and a thumb piece for rotating the first rollback in said one direction.

8. In a latch of the class described, a casing, a latch bolt slidable in said casing between a spring projected position and a retracted position, a pair of rollbacks, means mounting said rollbacks for coaxial rotation in said casing, means whereby one rollback retracts said latch bolt when it is rotated in one direction, means whereby the second rollback retracts said latch bolt when rotated in a reverse direction, means whereby the second rollback rotates the first rollback to retract the latch bolt when rotated in said one direction, a spindle traversing openings in both said rollbacks with the opening in the first rollback sufficiently large to allow free rotation of said spindle relatively thereto while the second rollback opening couples the second rollback to the spindle for rotation therewith in both directions, a lever pivoted on said casing and adapted when rotated on its pivot to rotate said first rollback in said one direction, and a thumb piece for rotating said lever.

9. In a latch of the class described, a casing, a latch bolt slidable in said casing between a spring projected position and a retracted posi-

tion, a pair of rollbacks, means mounting said rollbacks for coaxial rotation in said casing, means whereby one rollback retracts said latch bolt when it is rotated in one direction, means whereby the second rollback retracts said latch bolt when rotated in a reverse direction, means whereby the second rollback rotates the first rollback to retract the latch bolt when rotated in said one direction, a spindle traversing openings

10 5 15 in both said rollbacks with the opening in the first rollback sufficiently large to allow free rotation of said spindle relatively thereto while the second rollback opening couples the second rollback to the spindle for rotation therewith in both directions, a lever pivoted on said casing and adapted when rotated on its pivot to rotate said first rollback in said one direction, said lever having a portion extending outwardly of said casing, and a thumb piece for contacting the outwardly extending portion of said lever to rotate said lever.

14. In a latch of the class described; a casing, a latch bolt slidable in said casing between a spring projected position and a retracted position, a pair of rollbacks, means mounting said rollbacks for coaxial rotation in said casing, means whereby one rollback retracts said latch bolt when it is rotated in one direction, means whereby the second rollback retracts said latch bolt when rotated in a reverse direction, means whereby the second rollback rotates the first rollback to retract the latch bolt when rotated in said one direction, a spindle traversing openings in both said rollbacks with the opening in the first rollback sufficiently large to allow free rotation of said spindle relatively thereto while the second rollback opening couples the second rollback to the spindle for rotation therewith in both directions, the said spindle terminating substantially at the outer surface of said second rollback, and a limit member secured to said spindle and bearing against the outer surface of said second rollback.

15. In a latch of the class described; a casing, a latch bolt slidable in said casing between a spring projected position and a retracted position, a pair of rollbacks, means mounting said rollbacks for coaxial rotation in said casing, means whereby said rollbacks retract said latch bolt when rotated relatively to said casing, a spindle traversing openings in both said rollbacks, the said spindle terminating substantially at the outer surface of said second rollback, and a limit member secured to said spindle and bearing against the outer surface of said second rollback.

CHARLES LEDIN.
